UNITED STATES PATENT OFFICE

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY

SHOE NAIL

Original application filed June 16, 1920, Serial No. 389,397. Divided and this application filed October 25, 1926. Serial No. 143,971.

The present invention relates to fastening devices for shoes, it more particularly concerning nails adapted for the securing of heels to shoe-bottoms.

5 An object of the invention is to provide a nail or like fastening by which there may be obtained a firm union between the shoe-parts. An example of a highly useful application of this invention is found in the attachment of 10 heels of the Louis type, which, from a tread of small diameter and a still smaller neck rising from the tread, expand by a sharp curvature to a much greater diameter at the heel-seat. To drive the attaching nails straight 15 through such a heel vertically to the tread-surface, causes their clinching in the shoe-bottom to be so widely separated from the edge of the heel-seat-end as to produce little resistance to gaping at the rand-crease. If 20 the nails are driven in an inclined direction, only a small divergence can be given to entering extremities if their bodies are to remain within the walls of the contracted portion of the heel. The nails of this invention may be 25 kept safely within the neck of the heel, and yet the points caused to enter the shoe-bottom in such close proximity to the edge of the expanded portion that a good joint is assured.

This result is attained by the provision of 30 a novel nail having an inclined surface arranged to cause the deflection of its body-portion when this is driven, and a guide-projection in the form of a radial fin extending longitudinally of the body-portion and arranged to determine the direction of the deflection. This projection is preferably from 35 the side of the body of the nail in proximity to but spaced from the end opposite the point as well as from said point, and bears a definite 40 angular relation to the inclined surface. The extension of the body beyond the guide-projection gives a portion to receive a top-lift when the projection is in contact with the 45 tread-end of the body of the heel.

In the accompanying drawings,

Fig. 1 shows in side elevation a portion of a shoe with its heel attached by one form of my invention;

50 Fig. 2 is a plan view of the bottom of the

body of the heel before the application of the top-lift;

Fig. 3 illustrates the heel-body partially pricked or perforated in preparation for driving the nails;

55

Fig. 4 is a broken perspective view of one of my improved nails;

Fig. 5 is a partial front elevation of a heel-attaching machine by which these nails may be driven;

60

Fig. 6 is an enlarged sectional detail taken through the loading device and die-block of the machine, with a shoe to be heeled upon its jack and in co-operation with the die-block; and

65

Fig. 7 is a top plan view of the nail-receiving cylinder mounted upon the loading device.

At S in Fig. 1 appears the bottom counter-portion of a shoe having attached to it a heel H of the Louis type, the body of which has a neck-portion 10 of relatively small diameter, expanding slightly to the tread-end 12 and heavily in the opposite direction to the heel-seat-end 14, the rear and sides of the heel thus being upon ogee curves. The transverse dimension of the neck 10 may be as little as five-eighths of an inch, while at the heel-seat the diameter may be nearly three times this. Were the attaching nails N 70 driven straight through the heel into the shoe-bottom in a direction at right angles to the tread-surface, they would come within an area approximately of a ten cent piece, and would obviously be ineffective to hold the heel closely to the upper at the rand-crease. If the nails were driven along straight lines in an inclined direction to enter the shoe-bottom at the points illustrated in Fig. 1, they would, as indicated at x, lie almost at 75 the surface of the neck, where they might be struck by the trimming knife, injuring this and spoiling the heels. To keep the nails fully within the substance of the neck-portion and at the same time bring them into 80 the shoe-bottom well toward the periphery of the heel-seat, I employ my improved nails N, preferably in the manner described below.

For driving the nails N, I may utilize the heel-attaching machine illustrated in part at 85

100

Lin Fig. 5, this having a frame 16 carrying a die-block 18, with which co-operate a jack or work-support 20, reciprocatory drivers 22 and an oscillatory loading device or devices 24, each loading device including a loader-block 26. Instead of containing the usual nail-receiving passages, the die-block and loader-block, since the nails used with the type of heels now under consideration are long, are each bored to receive vertical, cylindrical holders 28 and 30, respectively, extending above the blocks and held in place by set-screws 32. Both holders are fixed as to their angular position about their longitudinal axes by keys 34, which are seated in recesses in the blocks. Through the holders are vertical nail-receiving passages 36 grouped according to the points at which the nails are to enter a heel H, pressed against the under side of the die-block and against the bottom of the shoe S which is jacked upon the work-support 20. When the loader-cylinder 30 is in the nail-delivering position over the die-cylinder 28, the two sets of passages 36 are in vertical alinement, so that the nails in the former, released by the usual shutter mechanism, will fall directly into the passages of the latter, there resting with their points upon the heel. Extending longitudinally of each of the nail-receiving passages in both holders and opening therefrom are slots 38 to admit lateral guide-projections 40 from the heel-attaching nails N. Each of these projections is in the form of a small fin struck out of the body of a nail, so that it is situated between depressions. The thickness of this fin is less than the diameter of the nail, and it extends longitudinally at one side, in proximity to but somewhat removed from the end opposite the heel-entering point. This point 42 is preferably formed by a surface 44 inclined, as by cutting or bending, from one side of the body to the other and bearing a definite angular relation about the longitudinal axis of said body to the projection 40, it being here shown as diametrically opposite to it. The body at other than the point is preferably of substantially uniform diameter throughout, giving, beyond the projection, a portion suitable to retain a top-lift pressed upon it. When the nails are inserted in the loader-passages, the combined relation between the slots 38, projections 40 and the heel H positioned upon the jacked shoe, presents the nail-points to the tread-surface of the heel-body with the inclined surfaces turned inwardly from the corresponding elements of the outer curved surface of the heel, opposite which the nails are to be driven. The angular positions of all these parts are clearly shown in Figs. 2 and 7. Since, when the nails are dropped into the passages in the loader-cylinder 30, but a relatively small portion have their projections fortuitously alined with the slots 38, I prefer

to provide means for turning the other nails about their longitudinal axes, so that the projections will be caused automatically to enter the slots. As herein illustrated, this means consists of inclined surfaces 46 situated between the slots at their upper extremities, these surfaces being furnished by a frusto-conical end of the cylinder 30. After the point of a nail has been introduced into one of the passages 36 of the cylinder 30 and dropped, its weight, when the projection 40 strikes a surface 46, causes the nail to rotate about its axis until the projection enters the slot, allowing said nail to proceed properly along the passage to the alined passage in the die-cylinder 28.

In attaching a shoe-heel by the use of nails N, since, to obtain the best results, the paths to be first followed by the nails should be substantially vertical to the tread-surface of the heel H which is to be attached to the shoe S, this heel is first perforated, as indicated at 48 in Fig. 3 of the drawings, by any suitable form of pricking machine to a depth at which the inner ends of the perforations are at or near the transverse plane of the heel at which the neck-portion begins to expand toward the heel-seat-end. This having been accomplished, the heel is associated with the jacked shoe in the attaching machine L, and forced in the customary manner against the die-block beneath the nail-passages in the die-cylinder 28. A load of nails N is dropped into the loader-cylinder 30, their projections 40 either directly entering the slots 38 or being turned into co-operation therewith by their contact with the surfaces 46. This load is transferred to the die-block, by which the nails are presented to the heel, and the loader being swung back to its initial position, the drivers 22 descend and force the nails into the heel. At first, as they pass through the pricked perforations, their paths are straight, as determined by such perforations, but when the points 42 penetrate the material of the heel at the ends of the perforations, the resistance opposing their advance exerts a component of force acting at right angles to the axes of the nails. This causes their gradual divergence from straight lines in directions opposite to the inclines 44, or toward the outside of the heel, these portions of the paths being curvilinear, as appears in Figs. 1 and 6 of the drawing. Such paths, being maintained in the proper relation to the outside of the heel by the perforations and by the relation between the guide-slots 38 and the nail-surfaces 44, cause the nails at all points between the tread-end and the heel-seat-end to be sufficiently removed from the sides so there is no danger of their breaking through or being struck by the trimming knife, and still the nails are brought to such clinching points 50 in the shoe-bottom that they are relatively close to the rand-crease, holding this against gaping.

The curvature of the nail-paths beyond the extremities of the perforations 48 will depend upon the character of the resistance offered to them and upon the inclination of the surfaces 44. This last factor is a controllable one, the degree of divergence from a straight path varying inversely as the inclination of the point. That is, the sharper the point or the more acute its angle with respect to the longitudinal axis of the nail, the less will be the departure of the nail from the vertical. Consequently, by properly forming the points of the nails, they may be caused to closely follow the sides of heels of different contour and to emerge into the desired proximity to the rand-crease. The action of the drivers 22 continues until the projection 40 strikes and bears with some pressure against the tread-end of the heel-body, it performing, in addition to its angular positioning function, that of the flange upon the well-known collar-nail, holding the heel-lifts against separation. Upon the extremities 52 of nails which project beyond the tread-end, a top-lift T is then spanked by the heel-attaching machine L in the usual manner, thus completing the heelng operation.

A shoe in which the nail of the present invention is employed and the method of heelng such a shoe herein disclosed are made the subject of an application filed June 16, 1920, and bearing the Serial No. 389,397, of which this case is a division, the application having matured into Letters Patent of the United States, No. 1,631,155 on June 7, 1927. The machine disclosed herein, by which the nail may be driven in performing the just-mentioned method, is claimed in co-pending application Serial No. 143,972, filed October 25, 1926.

Having described my invention, what I claim as new and desire to secure by Letters Patent of the United States is:

1. A shoe-nail comprising a body-portion having a point with an inclined surface arranged to cause the deflection of the body in a predetermined relation to a shoe when the nail is driven, and a radial guide-fin of less width laterally of the body than said body and extending longitudinally of the body at the side opposite the inclined surface.

2. A shoe-nail comprising a body having a point with an inclined surface arranged to cause deflection of the body when the nail is driven, and a guide-projection from the body arranged to determine the direction of deflection, said projection being spaced from the end of the body opposite the point to give a portion to receive and retain a top-lift when the projection is in contact with the tread-surface of the body of a heel.

3. A shoe-nail comprising a body with an inclined point arranged to cause the deflection of the body when the nail is driven, and

a radial guide-fin extending longitudinally of the body and arranged to determine the direction of deflection, said fin being spaced from the end of the body opposite the point to give a portion to receive and retain a top-lift when the fin is in contact with the tread-surface of the body of a heel.

4. A shoe-nail comprising a body having an inclined end, the body from said inclined end to its opposite extremity being of substantially uniform diameter, and a projection from the side of the body, said projection being situated between depressions in the body and spaced from both extremities thereof, the portion of the body at the side of the projection opposite the point providing means to receive and retain a top-lift.

In testimony whereof I have signed my name to this specification.

JOSEPH H. POPE.
